Primary Examiner — Joseph Kukella*Assistant Examiner* — Darryl J Dardenne(74) *Attorney, Agent, or Firm* — Ebisu International Patent Office(57) **CLAIM**

The ornamental design for a coffee dripper, as shown and described.

DESCRIPTION

1. Coffee dripper

1.1 : Perspective

1.2 : Bottom Perspective view

1.3 : Front

1.4 : Back

1.5 : Top

1.6 : Bottom

1.7 : Left

1.8 : Right

1.9 : Reference perspective view of embodiment

(Continued)

Thin lines on the surface shown in each of the drawings represent the shape of the surface in three dimensions; reproduction 1.9 is for reference purposes only and forms no part of the claimed design.

1 Claim, 9 Drawing Sheets
